UNITED STATES PATENT OFFICE.

THOMAS W. CONNOLLY, OF LOS ANGELES, CALIFORNIA.

WELL-DRILLING RIG.

1,033,990.

Specification of Letters Patent. Patented July 30, 1912.

Application filed November 3, 1909. Serial No. 526,112.

To all whom it may concern:

Be it known that I, THOMAS W. CONNOLLY, a citizen of the United States of America, residing at Los Angeles, in the county of Los Angeles and State of California, have invented a new and useful Well-Drilling Rig, of which the following is a specification.

This invention relates to well drilling rigs, particularly to the rotary type, and one object of the invention is to provide a simple and effective means for driving the drill and for regulating the feed of the drill up or down.

In rotary drills it has heretofore been the custom to remove the detritus by hydraulic methods consisting of constantly forcing water under hydraulic pressure down through the pipe to force the detritus up outside of the pipe with the water, and another object of the present invention is to provide simple mechanical means for removing the detritus, thereby dispensing with the hydraulic mechanism heretofore necessary.

Other objects and advantages of the invention will be brought out in the following description.

Referring to the drawings: Figure 1 is a side elevation of my improved well drilling rig, partly in section on line x^1-x^1 Fig. 2. Fig. 2 is a section on line x^2-x^2 Fig. 1. Fig. 3 is a plan view; the lower portion of the mechanism being omitted. Fig. 4 is a vertical, longitudinal section on an enlarged scale of the mechanism. Fig. 5 is a section on line x^5-x^5 Fig. 4. Fig. 6 is an enlarged, vertical section through the drill, and the sand lifter. Fig. 7 is a bottom view of the cutting shoe. Fig. 8 is a top view of the same.

1 designates the derrick having a platform 2 on which is mounted a frame comprising a base plate 3 and four uprights 4 which support a top plate or spider 5 which provides an upper bearing. Rotatably mounted above the base plate 3 which provides a lower bearing is a bevel gear 6, and above the bevel gear 6 is a controlling sheave 7, both bevel gear 6 and controlling sheave 7 being mounted on ball bearings 8, and the controlling sheave 7 is internally threaded forming a nut 9.

Extending through the nut 9 of the controlling sheave 7 and engaging the same is a screw threaded tube 10 which, as clearly

shown in Fig. 5, is provided with two longitudinal grooves 11 with which are engaged internal radial lugs 12 projecting inwardly from the bevel gear 6. The upper end of the tube 10 is slit at 13, as shown in Figs. 1 and 4 and the sections of the screw threads at the upper end are tapered to receive a clamping nut 14 by means of which the upper end of the tube may be clamped to a section of the boring casing 15.

16 is a driven shaft mounted in journal bearings 17 at one side of the derrick and upon the driven shaft 16 are loose pulleys 19 and 20, the loose pulley 20 of which may be caused to rotate with the driven shaft 16 by the clutch 22 engaging with the central cone member 16^a fixed to the driven shaft. The driven shaft 16 has two loose pulleys 23 and a tight pulley 24 which is adapted to be driven by either a cross belt 25 or straight belt 26 which may be operated by a belt shifter 27 to drive the driven shaft 16 in either direction from a main shaft 28. A pulley 29 on the main shaft 28 is adapted to be driven through the medium of a clutch 30 and a belt 31 extends from pulley 29 to a pulley 32 on a shaft 33 which carries a bevel pinion 34 which drives the bevel gear 6.

35 is a brake for controlling the controlling sheave 7.

A drum 36 on the shaft 28 operates a cable 37 and is controlled by the clutch 38. The cable 37 extends under the loose pulley 19 on the driven shaft 16 and thence up over a sheave 40 at the top of the derrick, as shown in Fig. 1, and is attached to a sand remover, which will be hereinafter described. A cable 41 extends from the loose pulley 20 on the driven shaft 16 to the controlling sheave 7 for operating the latter.

The pulley 40 has a shaft 43 which normally rests in notches 44 in cross bars 45 at the top of the derrick. Pivoted at 46 in the top of the derrick is a rock yoke 47, the outer end of which carries a counter-weight 48. A cable 49 is connected to the inner end of the yoke 47 and extends down to a hook 50 near the bottom of the derrick, as shown in Fig. 1. Secured on the arms of the rock yoke 47 are two stop brackets 51 which act to stop the shaft 43 from running down the rock yoke 47 farther than the position shown by dotted lines in Fig. 1.

The sand remover comprises a tube 52 which is loose enough to slide down inside

the boring casing 15 and at its lower end is provided with a series of hinged triangular shaped depending leaves 53 which when elevated serve to close the bottom of the tube 52. Within the tube 52 is a series of rods 54 slidably supported in lugs 55 and at their upper ends are connected to a swivel 55' which is attached to the cable 37, before referred to. Screwed on the lower end of the boring casing 15 is the cutting shoe 56 having serrated cutting teeth 57 at its lower face which operate when the boring casing is descending, and having cutting teeth 58 on its upper edge which serve to clear out clay, sand or water from the hole outside the boring casing as the boring casing ascends.

In operation the bevel gear 6 is rotated through the aforescribed connections, the clutch 30 being thrown in, and through the medium of its internal lugs 12, engaging with the longitudinal grooves 11 imparts rotation to the tube 10 and the latter being clamped to the boring casing by the nut 14 imparts rotation to the boring casing 15, so that the cutting shoe 56 cuts the hole and throws the detritus toward the center of the hole. As the tube 10 thus rotates the controlling sheave 7, which is threaded thereon, rotates with it, except when the controlling sheave is held stationary, and thus so long as the controlling sheave 7 rotates with the tube 10, there is no differential movement between these two parts tending to move the tube longitudinally. When, however, it is desired to cause the drill to be fed down, the brake 35 is operated to hold the controlling sheave 7 still, whereupon as the tube 10 continues to revolve 40 it will be screwed down through the stationary controlling sheave 7, thereby lowering the drill and boring casing 15. It should be understood that when the controlling sheave 7 is thus allowed to rotate with the tube 10 or is caused to stand motionless under the brake 35 that under either of these two conditions the clutch 22 is set so that pulley 20 is idle on the shaft 16. Whenever it is necessary to elevate the boring casing 15 and drill, the brake 35 being released, the clutch 22 is thrown in, thereby causing the pulley 20 to rotate with the shaft 16, which results in driving the controlling sheave 7 at a speed faster than the tube 10 is driven by the bevel gear 6, which differential rotating movement results in imparting a reverse longitudinal movement to the tube 10 causing the latter to ascend together with the boring casing 15 and drill. The rate of this ascending movement will depend upon the difference between the two speeds of the bevel gear 6 and controlling sheave 7, both of which are running in the same directions, but the controlling sheave 7 running fastest. However, under ordinary

conditions the bevel gear 6 will not be running when the boring casing 15 is to be elevated and, therefore, the ascending movement of the tube 10 and boring casing 15 at such times will have as great a speed as when it is being fed downward. As the tool 57 throws the earth to the center the sharp pointed depending leaves 53 descend in the loose detritus and when a sufficient amount has accumulated within the tube 52 the cable 37 is operated by throwing clutch 38 in so that drum 36 revolves with shaft 38, thereby lifting the rods 54 and swinging the leaves 53 into closed position to confine the detritus within the tube 52. Continued upward pulling on the cable 37 results in lifting the tube 52 out of the boring casing 15 and as soon as that has been accomplished the cable 49 is released from the hook 50, whereupon the weight 48 overcoming the weight of the tube 52 and its contents tilts the yoke 47 into the position shown in dotted lines in Fig. 1, thereby lifting the shaft 43 out of the notches 44, whereupon the weight of the tube 52 and its contents acting through the cable 37 on the sheave 40 causes the latter to roll down on the yoke 47 until the shaft 43 strikes the stops 51, whereupon the shock of striking the stops 51 is such that a jerk or reaction on the cable 37 loosens the leaves 53 sufficiently to permit the detritus to drop out and be discharged in a heap at one side of the derrick, as shown in Fig. 1. Then the cable 49 is pulled down and reengaged with hook 50 and the pulley 40 runs back into its original position with its shafts resting in the notches 44. Then the cable 37 is retracted to lower the tube 52 into the boring casing 15 and down to the bottom thereof.

What I claim is:—

1. A well drilling rig comprising a derrick having a platform, a base plate providing a lower bearing, a spider providing an upper bearing, uprights by which the spider is supported on the base plate, a bevel gear having internal radial lugs and mounted on the base plate, a drive shaft having a bevel pinion meshing with the bevel gear, a controlling sheave having an internal screw thread providing a nut and mounted on the bevel gear, an externally screw threaded tube formed with longitudinal grooves engaged by the radial lugs of the bevel gear, a boring casing supported on and secured to the tube, and means for driving the controlling sheave.

2. A well drilling rig comprising a derrick having a platform, a base plate providing a lower bearing, a spider providing an upper bearing, uprights by which the spider is supported on the base plate, a bevel gear having internal radial lugs and mounted on the base plate, a drive shaft having a bevel pinion meshing with the bevel gear, a

controlling sheave having an internal screw thread providing a nut and mounted on the bevel gear, an externally screw threaded tube formed with longitudinal grooves engaged by 5 the radial lugs of the bevel gear, and with a slotted upper end providing screw threaded tapered sections, a clamping nut mounted on the tapered sections, a boring casing supported on and secured by the clamping

nut to the tube, and means for driving the 10 controlling sheave.

In testimony whereof, I have hereunto set my hand at Los Angeles, California, this 28 day of October 1909.

THOMAS W. CONNOLLY.
